UNITED STATES PATENT OFFICE.

WALTER FRANKLIN PILCHER, OF DOOTHAN, ALABAMA, ASSIGNOR OF ONE-HALF TO
HENRY A. POWELL, OF DOOTHAN, ALABAMA.

SWING.

1,136,262.

specification of Letters Patent. Patented Apr. 20, 1915.

Application filed July 11, 1913. Serial No. 778,557.

To all whom it may concern:

Be it known that I, WALTER FRANKLIN PILCHER, a citizen of the United States of America, and a resident of Dothan, in the 5 State of Alabama, have invented a new and useful Improvement in Swings, of which the following is a specification.

This invention relates to suspended swings of what may be termed the settee 10 type, and consists in the improvement hereinafter particularly set forth and claimed.

The leading object of this invention is to adapt a slightly settee-shaped swing to be readily and quickly converted into a safe 15 cradle or infant's swing without the aid of detached parts.

Other objects will be set forth in the general description which follows.

A sheet of drawings accompanies this 20 specification as part thereof.

Figure 1 is a perspective view of the improved swing; Fig. 2 represents a cross section through one seat etc., corresponding with Fig. 1; Fig. 3 is a corresponding section of the converted swing; Fig. 4 is a fragmentary sectional view; Fig. 5 is a view of one of the slide pivots detached; and Fig. 6 is a fragmentary sectional plan projected down from Fig. 3.

Like reference characters refer to like 30 parts in all the figures.

The improved settee-shaped swing is preferably and conveniently constructed with a pair of seats, 1 and 2, and with corresponding 35 individually reversible backs, 1' 2'; and is more particularly characterized by a converting slide, 3, normally inclosed beneath one of the seats, for example the seat marked 2, and adapted to be withdrawn and fastened up as in Fig. 3 so as to close 40 what is herein termed the front of the space above that seat; the back 2' being in position at the opposite edge of the seat, as shown in Figs. 1-3. The swing is thus readily adapted without detached parts to securely retain an infant placed between said back 2' and fastened up slide 3 on the seat 2; while an attendant may comfortably occupy the adjoining seat 1; or two persons 50 may occupy the respective seats 1 and 2, facing either in one and the same direction or in opposite directions, the slide 3 being inclosed out of the way as in Figs. 1 and 2.

A bottom frame, 4, common to both the 55 seats 1 and 2, supports rigidly a pair of ends

5 and 6 and a partition member 7; said ends being provided in common with means for attaching thereto ropes or chains for suspending the body of the swing. Such means, which may be of any known or improved kind, are represented by holes, 8, with a hook 8°, beneath each hole, in Fig. 1. Hinge members 9 rigidly attached to the respective backs 1' and 2' are attached to the opposing faces of said ends 5 and 6 and partition 7 by pivots, 10, Figs. 2 and 3, in a customary way. The converting slide 3 is supported within the bottom frame 4 upon a pair of strips 11, Fig. 4, adjoining which a pair of guide grooves or ways, 12, Fig. 4, are formed in the frame 4. These ways are closed by the front strip 4' of the frame 4, which is provided with a slot, 13, through which the slide is withdrawable. The stop portions 4" of said front strip 4' which 75 close the ways 12 in front, as aforesaid, are located on the ends of the slot 13. Fig. 6 shows a section through one of said stop portions 4".

The movements of the slide 3 are controlled by a pair of crank-shaped pivots, 14, Figs. 4 and 5, having head ends 15, Fig. 5, projecting laterally away from the slide and fitted loosely to said ways 12, shanks 16, Fig. 5, parallel to the lateral 85 edges of the slide, and pivotal screw ends 17, Fig. 5, at right angles to said shanks, which are screwed into the said lateral edges of the slide. When the slide is withdrawn as represented by the arrow *a* in Fig. 2, said 90 heads 15 of the pivots 14 contacting with said stop portions 4" of said front strip 4' as in Fig. 6, prevent its separation from the body of the swing, while said shanks 16 permit it to clear the front of the frame 95 4, so as to be turned on the pivotal screw ends 17, as represented by the arrow *b*, Fig. 2, into the effective position in which it is shown by Fig. 3. For fastening the converting slide 3 in said effective position, the 100 partition 7 and end 6 are provided with buckles, 18; and the slide 3 with matching straps 19. Other fastenings may obviously be substituted for said buckles and straps 18, 19; a converting slide 3, as above described, may be provided for each of the seats 1 and 2, if preferred; and other like modifications will suggest themselves to those skilled in the art.

Having thus described said improvement, 110

I claim as my invention, and desire to patent under this specification:

1. A convertible swing having a bottom frame constructed with ways closed in front and a front slot between said ways, a superjacent seat, a back therefor, a converting slide normally inclosed beneath said seat, a pair of crank-shaped pivots for said slide each comprising a stop-forming head end 5 projecting laterally away from the slide, a shank parallel to the adjoining lateral edge of the slide and a screw end, at right angles to said shank, screwed into said lateral edge, and upon which said slide can be turned upward after it is withdrawn through said slot, and means for fastening the upturned slide in its effective position.
2. The combination, in a settee-shaped swing body, of a bottom frame including a slotted front member and constructed with ways closed in front by said slotted member and a front slot between said ways, a superjacent seat, a back therefor, a converting slide normally inclosed beneath said seat and withdrawable through said front slot; a pair of crank-shaped pivots for said slide each comprising a stop-forming portion movable within one of said ways, a shank 10 15 20 25

parallel to the adjoining lateral edge of said slide, and a pivot portion at right angles 30 to said shank upon which said slide can be turned upward after it is withdrawn; and means for fastening the slide in its upturned position; substantially as hereinbefore specified.

3. The combination, in a convertible swing, of a bottom frame comprising a pair of ways and a slotted front piece having stop portions which close said ways in front, a superjacent seat, a converting slide normally inclosed beneath said seat, and a pair of crank-shaped pivots for said slide each comprising a stop forming head within one of said ways adapted to contact with the corresponding stop portion of said front 40 45 piece, a shank parallel to the adjoining lateral edge of said slide, and a screw end, at right angles to said shank, screwed into said lateral edge, and upon which said slide can be turned upward after it is withdrawn 50 through said slot; substantially as hereinbefore specified.

WALTER FRANKLIN PILCHER.
